UNITED STATES PATENT OFFICE.

JAMES NAPOLEON DODGE, OF SPRINGFIELD, MASSACHUSETTS, ASSIGNOR OF
ONE-HALF TO SOLOMON J. GORDON, OF SAME PLACE.

INHALER.

SPECIFICATION forming part of Letters Patent No. 297,769, dated April 29, 1884.

Application filed October 25, 1883. (No model.)

To all whom it may concern:

Be it known that I, JAMES NAPOLEON DODGE, of Springfield, Hampden county, State of Massachusetts, have invented a new and useful Improvement in Inhalers, which is fully set forth in the following specification and accompanying drawings, in which—

Figure 1 is an exterior view of my improved inhaler; Fig. 2, a front end view of the same; Fig. 3, a longitudinal cut section thereof; Fig. 4, a side view of the absorbing-conduit; Fig. 5, a rear end view of the inhaler.

This invention relates to that class of apparatus for administering anaesthetics in which the absorbent material is inclosed in a case, through which the patient is caused to inhale, a suitable reservoir being connected with such inclosing-case for supplying the anaesthetic in regulated quantities to the confined absorbent material.

My improvement consists of certain novel constructions and combinations, which are clearly pointed out in the claims at the close of this specification.

In the drawings, A represents the exterior inhaling-case; B, the reservoir; C, the absorbing-conduit; D, the neck of case A; E, the rubber mouth-piece; F, the gate; H H, the openings thereof; I I, the conduit-ribs; J, the reservoir-pipe; K, the slot by which it enters case A; L, the thumb-screw to control the position of reservoir B; M, the mouth of reservoir B; N, its cap-screw; O, the air-inlet; P, its cap-screw; R, the hinged cover; S, its securing catch-spring; T, the slide-frame that operates it; U, its push-pin.

Over and under each rib of conduit C flannel is wound in the form of a continuous strip, which leaves an open space, the depth of a rib, between the upper and under surfaces. Within this space I place a card of thin blotting-paper. The flannel and the paper form a simple, convenient, and most effective saturating apparatus, easily renovated at trifling cost. Felt answers the purpose well; or any absorbent material may be used to take up the fluid and diffuse it over an extended surface, to retain and gradually impart its properties to the air contained in the inhaling-case, which the patient is to breathe.

The action of my improved apparatus will be readily understood. Reservoir B is filled with the ether or other insensibility-producing agent, and its mouth M closed by cap N. Elevating the rear of reservoir B brings its pipe J within orifice K of case A, so that the fluid, escaping from the end of pipe J, will be brought into immediate contact with the flannel encircling ribs I I of conduit C, or whatever absorbent material is employed in the conduit as a surface-distributer. Tightening thumb-screw L secures reservoir B at any desired angle, to facilitate the escape of the anaesthetic, and opening air-inlet O by thumb-screw P promotes the flow, if necessary. If the patient is in a sitting position, rubber mouth-piece E may be quite straight; but if in a recumbent attitude, a curved form will be more convenient. Rubber mouth-piece E being held firmly against the mouth and over the nose of the patient, the operator has only to regulate the admission of external air by opening and closing gate F by the little knob seen thereon in Fig. 2, and the inward aspiration of the patient will draw the desired influence from the saturated absorbent material on the ribs of conduit C by the natural action of the lungs.

If preferred, reservoir B may be dispensed with. Pressing push-pin U relieves, through slide-frame T, the catch of securing-spring S, and hinged cover R flies open, and the anaesthetic agent may be dropped from a vial directly upon the absorbent material of conduit C, and cover R closed.

What I claim as my invention, and desire to secure by Letters Patent, is—

1. The combination, substantially as before set forth, with the case provided at one end with a flexible mouth-piece and at the opposite end with an adjustable air-gate, of the removable saturation-conduit, which consists of a ribbed cage and a strip of flannel wound back and forth across the cage around the ribs thereof.

2. The combination, substantially as before set forth, of the case provided at one end with a flexible mouth-piece and at the opposite end with an adjustable air-gate, the removable saturation-conduit, constructed as described,

and the adjustable hinged anæsthetic-reservoir provided with a drop-tube.

3. The anæsthetic-reservoir provided with a drop-tube and an adjustable vent-valve.

5 4. The combination, substantially as before set forth, of the case containing the saturation-conduit, the hinged cover thereof, and the adjustable hinged anæsthetic-reservoir pro-

vided with a drop-tube passing through a slot in said hinged cover of the case.

JAMES NAPOLEON DODGE.
